UNITED STATES PATENT OFFICE.

SUMNER S. COBB, OF ROCHESTER, NEW YORK, ASSIGNOR TO THE METALLIC BASKET COMPANY, OF SAME PLACE.

METALLIC WASHTUB.

SPECIFICATION forming part of Letters Patent No. 657,087, dated September 4, 1900.

Application filed August 24, 1899. Serial No. 728,302. (No model.)

To all whom it may concern:

Be it known that I, SUMNER S. COBB, a citizen of the United States, residing at Rochester, in the county of Monroe and State of New York, have invented an Improvement in Metallic Washtubs, of which the following is a specification, reference being had to the accompanying drawings.

My invention relates to an improved wringer attachment for metallic washtubs, which improvement is fully described and illustrated in the following specification and the accompanying drawings, the novel features thereof being specified in the claim annexed to the said specification.

In the accompanying drawings, representing my invention, Figure 1 is a side elevation of a metallic washtub with my improved wringer attachment. Fig. 2 is a plan view of the same. Figs. 3, 4, and 5 represent the attachment on a larger scale. Figs. 6 and 7 represent modifications.

In the manufacture of my improved wringer attachment I take a strip B of suitable sheet metal and corrugate and divide it to produce plates A, having ribs C or the like of suitable shape and dimensions, and I attach two of such plates to the outside of the washtub D, near its upper edge, at a distance apart which corresponds with the clamps of the wringer. The flanges or corrugations project outward from the body of the tub and provide additional thickness to its wall at points designed for the attachment of wringer-supporting clamps, whereby the leverage of the wringer and its supporting clamp members is diminished. The plates are secured to the tub by rivets E or other suitable devices, or they may be secured by soldering or by galvanizing the whole structure either with or without the rivets. The ends of the corrugations may be left square, as indicated at F, Fig. 3, or they may be beveled or rounded, as at H, or the corners may be folded down sidewise, as shown at I, Fig. 5. The inner sides of the corrugations may be in contact, or they may be formed with an interval between them, as indicated in Fig. 4, which is a section on the line 4 4, Fig. 5.

In a modification represented in Fig. 7 the

corrugations are arranged horizontally; but the horizontal arrangement is not essential. The corrugated strips attached to the wall of the tub supplement its thickness, with the effect to increase the distance between the co-operating bearing-faces of the clamps, whereby the leverage of the wringer, acting transversely of the side wall of the tub, is decreased, said wall contiguous the corrugated pieces being also thereby stiffened. This avoids the evil of buckling or bending of the thin sheet-metal wall of the tub, as when the clamps are applied directly thereto and bite or clamp it closely.

As sheet metal is used for the attachment, it is cheap and light and adds but little to the cost or weight of the tub. The attachment becomes a part of the tub itself, so that it is always ready for use. It is impossible to detach it, and it will last as long as the tub. The galvanizing prevents the entrance of the soapy water between the plates and body. The rounding or folding in of the corners of the ribs obviates any sharp projections and so prevents damage to any clothes which may come in contact with the attachment.

In the modification shown in Fig. 6 the bosses J or projections of other shapes are pressed into the metal, so as to virtually increase the thickness of the metal and adapt it, in co-operation with the tub-wall proper, to hold the clamping-screws and wringer in the same way as do the ribs or corrugations. These projections may be of any suitable dimensions, form, or arrangement, provided they are sufficiently numerous and close together to support the contiguous clamp-faces at a distance from the tub-wall when the clamps are in operation, and they should have sufficient strength and rigidity to prevent collapse under the pressure of the clamps or leverage of the wringer. Preferably the plates will be situated contiguous the tub-top and between it and horizontal ribs in the tub-wall, as indicated in Fig. 1.

The manner of using my improvement will be understood from Fig. 1, in which the wringer is shown attached to the tub, its clamping-screws bearing against the thickening-plates of the wringer attachment.

It will be understood that I do not claim, broadly, a thick washtub-wall, but the particular attachment formed and applied to a thin-walled washtub, as and for the purpose

5 set forth.

I claim—

In combination with a washtub, a wringer

attachment comprising metal plates fixed to the tub, said plates being thickened by transverse projections formed in the metal.

SUMNER S. COBB.
